UNITED STATES PATENT OFFICE

JAMES J. SANTIAGO, OF LOS ANGELES, CALIFORNIA, ASSIGNOR TO JOHN GRANT, OF LOS ANGELES, CALIFORNIA

ROTARY EXPANSION UNDERREAMER

Application filed January 12, 1927. Serial No. 160,580.

This invention has reference generally to underreamers and particularly to rotary expandable underreamers such as are adapted to precede a well casing and drill a hole below the casing large enough that the casing may be lowered into it. Rotary expandable underreamers are well known and are in common use so that no detailed description of their operation is here necessary.

10 The present invention has to do more particularly with improvements in that type of underreamer shown in patent to Brown No. 1,454,843, dated May 15th, 1923, and also in the pending applications of John T. Phipps, Serial Number 75,275, filed Dec. 14, 1925; 15 Serial Number 64,839, filed Oct. 26, 1925; and Serial Number 61,808, filed Oct. 10, 1925.

In the type of underreamer shown in said patent and applications the cutters are 20 mounted within a tubular body or shell and project out through slots in the body wall, being backed up when in their expanded position by an interior core or mandrel. The cutters and mandrel are so shaped that relative longitudinal movement between the 25 cutters and mandrel causes expanding and collapsing movements of the cutters. In both said patent and said applications such longitudinal movement is accomplished by having 30 the cutters longitudinally movable in or with reference to the tubular body, the mandrel being stationary with relation to the tubular body. In the present invention, among other things, this relative arrangement is reversed, the interior mandrel and the body moving 35 longitudinally with reference to each other so that the cutters are longitudinally stationary with reference to the body and move only in and out transversely. There are also 40 several other improvements that are included within the present invention; but all these improvements will be better understood from the following detailed explanation of the 45 present preferred form of the invention, which may be taken as typical and illustrative of the invention itself.

In the accompanying drawings:

Fig. 1 is a longitudinal vertical central 50 section with some parts in elevation showing

my improved underreamer in its expanded condition;

Fig. 2 is a similar view showing the underreamer in its contracted condition;

Fig. 3 is a view partly in section and partly in elevation, the section being taken as indicated by line 3—3 on Fig. 2; 55

Fig. 4 is an exterior elevation of the underreamer;

Fig. 5 is a cross-section on line 5—5 of 60 Fig. 2;

Fig. 6 is a cross-section on line 6—6 of Fig. 2; and

Fig. 7 is a cross-section on line 7—7 of 65 Fig. 2.

In the drawings the body B of my improved underreamer is shown as made up of two parts, or a body proper and an extension; an upper tubular body or shell 10 and a lower tubular body portion or extension 11, the two being joined at the threaded joint 12 and shouldering tightly against each other at the shoulders 13. The upper tubular shell 10 has through its wall a number of slots 15 through which the cutters 16 project. In the typical embodiment here illustrated I have shown the slots and cutters as two in number, but it will be well understood that there may be as many cutters as desired. Whatever the 70 number of cutters, it is desirable that they be placed in symmetric relation about the vertical central axis of the reamer, so that the reaction forces playing upon the cutters will be balanced and will not tend to shove the underreamer off to one side or another during 75 drilling operations. 80

Typically the cutters may preferably be of rather flat formation, more or less in the shape of a flat bar; and they may be provided with outer edges, or outer and lower edges; with any suitable cutting elements. It is common in underreamers of this type to provide the cutters with sharp edges that shear away the formation; and cutters of that type may be used in this underreamer, but 85 I have preferred here to illustrate how I may provide rolling cutting elements 17 which project somewhat beyond the outer edges of cutters 16 and operate upon the formation in manners that are well understood. To pro- 90

vide for the cutters moving inwardly to the position shown in Fig. 2 the slots 15 have enlargements 18 forming recesses into which the innermost parts of rollers 17 may move. 5 This arrangement will be apparent from an inspection of Figs. 2 and 4.

Within the body of the underreamer there is a mandrel 20 provided at its upper end with any usual tool joint 21 for connecting with the drilling string. Within the upper body member 10 this mandrel has an enlargement 20^a, and an inwardly extending flange 22 at the upper end of body portion 10 limits the downward movement of the body with relation to the mandrel and prevents the mandrel 15 from being pulled out of the body.

Enlarged portion 20^a of the mandrel is provided with two diametrically opposed slots 23 which take the inner edges of cutters 16 in the manner illustrated in the drawings. The inner edges of the cutters and the bottom surfaces of these slots are so relatively shaped that relative vertical motion between the cutters and mandrel causes expanding and collapsing movements of the cutters. I prefer to give the cutters two spaced thrust bearings upon the mandrel to support the cutters outwardly in their drilling positions. The reason for my preference in this regard is that two such spaced thrust bearings, arranged near opposite ends of the cutters, give the cutters a very strong and solid support, quite as strong and solid as one continuous thrust bearing the whole length of a cutter will give; and the two spaced bearings have the advantage that the cutters and body need not be moved longitudinally as far as they would have to be moved if there were a single thrust bearing the entire length of the cutter.

Accordingly I make slots 23 each with a recess 23^a in its bottom or inner surface, as will be clearly seen from an inspection of Fig. 1. Each cutter has near or at its upper end an inwardly projecting thrust lug 16^a which fits into recess 23^a when the cutter is in its lower position on the mandrel as shown in Fig. 2. At the same time that lug 16^a fits into recess 23^a another similar thrust lug 16^b near or at the lower end of the cutter then fits against the lower reduced part 20^b of the mandrel, as shown in Fig. 2. The mandrel may be said to have two recessed portions into which the two thrust lugs 16^a and 16^b move back when the cutters are in their collapsed or inner positions, the upper recessed portion comprising the recess 20^a and the lower recessed portion being comprised, in effect, in the reduction of diameter of the mandrel below its enlarged part 20^a.

In the expanded position the two thrust lugs 16^a and 16^b of each cutter bear upon the bottom surface 23^b of the unrecessed portions of slots 23 as shown in Fig. 1. The upper ends of both thrust lugs are beveled off as shown at 16^c, and the upper end of

recess 23^a is similarly beveled at 23^d and the lower end of the enlarged part of the mandrel is also similarly beveled at 23^e, so that when the parts move from the position of Fig. 2 to the position of Fig. 1 the cutters will be forced outwardly by the wedging actions of these beveled faces. When the cutters are thus forced out to their expanded positions the cutters are solidly supported against inward radial thrust by having solid and widely spaced bearings upon the interior mandrel. And the cutters are solidly supported against torsional strains by reason of their fitting fairly tightly in slots 15, being only loose enough in those slots to provide for easy movement. The cutters also fit in slots 23 of the mandrel, but they fit those slots comparatively loosely for reasons to be hereinafter explained. And the cutters are prevented from being pulled or torn out of their slots by direct radial outward movement by reason of cutter projections 16^e at their upper and lower ends, these projections bearing outwardly against the wall of body shell 10 above and below the slots 15.

The lower reduced end 20^b of the mandrel projects down into the bore 11^a of body extension 11 and is there surrounded by a coiled spring 30 whose upper end presses against a shoulder at the upper end of bore 11^a and whose lower end is seated on a ring 31 carried by the mandrel. The function of this spring is to press the body up with relation to the mandrel, tending always to move the parts to the position of Fig. 1. The mandrel and body are moved to the relative positions shown in Fig. 2 whenever it is desired to collapse the cutters. This is done by the operator at the top of the well when it is desired to lower the underreamer into the hole, and is accomplished automatically when the underreamer is raised up into a casing. When mandrel 20 is moved upwardly into the casing the upper ends of the parts of the cutters that project outside the body portion 10 come into contact with the lower end of the casing or with its shoe and hold the body stationary while the mandrel moves on up to the relative position shown in Fig. 2. Then the bevels 16^c on the upper ends of the cutters, acting against the casing shoe, cause the cutters to move into the positions shown in Fig. 2; and then the whole underreamer may be pulled up through the casing.

Lower body extension 11 is provided at its lower end with a threaded joint 35 to take a drilling bit 36 of any desired type, but here typically illustrated as a fish-tail bit. To get circulating water to the fish-tail bit it is provided with a water duct 37; and mandrel 20 is likewise provided with a water duct 38 extending through its entire length and connecting with the water duct or hollow interior of the drill pipe that is attached at the upper end of the mandrel. Water put down through

the drill pipe will thus be delivered through the mandrel to bore 11^a of the lower body extension 11, and thence to the water duct 37 of the drill bit. And water will likewise be delivered directly under cutters 17 by ducts 39 that lead upwardly and outwardly from bore 11^a. The cuttings from cutters 17 are being continuously moved up by the upwardly flowing stream of liquid around the underreamer; and the ducts 39 provide for delivery of a portion of the liquid upwardly under cutters 17. Thus a portion of the total liquid circulation goes directly to the lower bit 36 to pick up its cuttings and a portion goes directly to the reaming cutters to pick up their cuttings.

The upper end of lower body extension 11 screws into and shoulders up against the lower end of the upper body shell 10. The upper end of portion 11 is interiorly beveled as at 40 to seat the bevel 23° of the mandrel. And the upper end of 11 is provided with one or more notches 41, two being shown diametrically opposite each other. The mandrel 20 has at the lower end of its enlarged portion 20^a a corresponding number of lugs 42 adapted to fit more or less loosely into notches 41 when the parts are in the position shown in Fig. 1.

The lower ends of lugs 42 are beveled, as shown at 42^a so that the lugs will be guided into notches 41 as the parts move to the position of Fig. 1.

Lugs 42 and notches 41 constitute a positive rotary drive between mandrel 20 and lower body extension 11, which carries the drilling bit at its lower end; and this lug and notch interengagement not only provide such a positive drive, but also totally prevents any accidental unscrewing of lower body member 11 when the parts are in the position of Fig. 1. This is the expanded position and is one in which the positive drive is needed and the one in which unscrewing is most likely to occur. When the underreamer is collapsed, as shown in Fig. 2, there is no need of this positive drive and lock between the parts, and in that position lugs 42 are raised out of notches 41.

The rotary drive of the whole tool is through the mandrel 21. This mandrel drives cutters 16 by the engagement of those cutters in the mandrel slots 23, and drives the upper body shell 10 through the medium of cutters 16. The looseness of fit of the cutters in slots 23 allows a certain latitude in the exact positions of notches 41, the exact position of those notches being determined by the position at which part 11 shoulders up against the lower end of part 10. The rotary drive is usually in a right-handed direction looking down on the tool, or in the direction indicated by the arrow in Fig. 5, and the thread at 12 will usually be a right-handed thread, so that the drive tends to tighten up the

thread. The thread, however, cannot tighten up any further than the interengagement of 41 and 42 allows, and, consequently, the actual drive, or the major portion of it, will be taken by 41 and 42 rather than by the threads 12. And if at any time it should be necessary to rotate the expanded tool backwardly, the joint at 12 cannot be broken. The slight looseness of cutters 16 in slots 23 also prevents the cutters becoming bound in the slots by fine silt. Fluid can always play through the slots around the cutters and thus keep the cutters free.

Although the construction is such that the parts are all completely interlocked when the underreamer is expanded and operating, and the parts are thus locked against any possible disconnection, at the same time the construction is such that the underreamer is easily assembled and disassembled. To take the underreamer apart it is only necessary to move mandrel 20 up far enough to disengage lugs 42 from notches 41. Then after ring 31 and spring 30 have been removed, extension 11 may be unscrewed and removed. The joint or joint member at the top of mandrel having been removed, the mandrel may then be slipped downwardly and out of shell 10, or the shell slipped up off the mandrel; and the cutters may then be moved inwardly and removed through the bottom of the shell. The assembly is in the reverse order.

I claim:

1. An underreamer of the character described, comprising a tubular body with a slot through its wall, a cutter extending through said slot and confined against longitudinal movement therein but movable laterally in and out through the slot, and a mandrel in the body, with relation to which it is longitudinally movable, and having a longitudinal slot in its surface taking the inner edge of the cutter and constituting a rotary driving connection between the mandrel and the cutter; the body having a lower extension screw-threadedly joined to it, and the mandrel and said body extension having interengaging lug and notch structures adapted to interengage when the mandrel is in a certain position with reference to the body.

2. An underreamer of the character described, comprising a tubular body with a slot through its wall, a cutter extending through said slot and confined against longitudinal movement therein but movable laterally in and out through the slot, and a mandrel in the body, with relation to which it is longitudinally movable, and having a longitudinal slot in its surface taking the inner edge of the cutter and constituting a rotary driving connection between the mandrel and the cutter; the body having a lower extension screw-threadedly joined to it, and the mandrel and said body extension having interengaging lug and notch structures adapt-

- ed to interengage when the mandrel is in a certain position with reference to the body, said lug fitting the notch loosely and said cutters fitting the mandrel grooves loosely.
5. An underreamer of the character described, comprising a tubular body with a longitudinal slot extending through its wall, a cutter in said slot and projecting both outside and inside the body wall, said cutter fitting said slot to be immovable longitudinally therein but movable laterally in and out through said slot, a mandrel in said body and with relation to which it is longitudinally movable, the inner edge of said cutter engaging said mandrel, and said cutter and mandrel being so formed that relative longitudinal movement between the body and mandrel causes lateral movement of said cutter, a body extension screw-threadedly joined to one end 10 of the body, and an interengaging lug and notch formation on the mandrel and said body extension and adapted to be engaged by longitudinal movement of the mandrel.
15. An underreamer of the character described, comprising a mandrel, a tubular body and a body extension removably joined to the body at one end, the body and extension surrounding and being longitudinally movable on the mandrel, a cutter in the body adapted to be moved outward to expanded position by longitudinal movement between the body and mandrel in one direction, said cutter engaging the mandrel to rotationally interlock the body and mandrel, and rotational 20 interlocking means between the mandrel and said body extension adapted to be put into interlocking engagement by the relative longitudinal movement which expands the cutters.
25. An underreamer of the character described, comprising a slotted cutter expanding mandrel having means at its upper end for connection to a rotary driving string, a slotted body surrounding the mandrel, and a cutter engaging in both slots to be rotatively driven by the mandrel and in turn to rotatively drive the body, the body and cutter being longitudinally movable with reference to the mandrel to protract and retract the cutter, a body extension movably joined thereto, and rotative interlocking means on the mandrel and extension adapted to be engaged when the body and mandrel are relatively in cutter protracting position and disengaged when the body and mandrel are relatively in cutter retracting position.
30. An underreamer of the character described, comprising a body, a cutter movable therein, a cutter expanding mandrel movable relatively longitudinally in the body, a body extension removably mounted on the body, and rotational interlocking means on the mandrel and extension adapted to be engaged by movement of the mandrel to cutter expanding position.
35. An underreamer of the character described, comprising a body, a cutter movable therein, a cutter expanding mandrel formed to move the cutter outwardly by downward movement of the mandrel, a lower body extension into which the lower end of the mandrel projects, a mandrel operating spring surrounding the mandrel in the body extension and tending to move the mandrel down, and rotational interlocking members on the mandrel and extension adapted to be engaged by downward spring actuated movement of the mandrel.
40. An underreamer of the character described, comprising a body, a cutter movable therein, a cutter expanding mandrel movable relatively longitudinally in the body, a spring surrounding the mandrel and tending to move it longitudinally in a direction to move the cutter outwardly, a body extension, and rotational interlocking members on the extension and mandrel adapted to be engaged by the spring actuated movement of the mandrel.
45. An underreamer of the character described, comprising a tubular slotted body, a slotted mandrel within the body, a cutter in the body slot and having its inner longitudinal edge in the mandrel slot, the cutter and mandrel being relatively longitudinally movable, the mandrel slot having a recess in its bottom intermediate its ends and the mandrel presenting at one end of the slot a surface which is sunk inwardly from the slot bottom, and the cutter having a pair of spaced lugs on its inner longitudinal edge adapted one to lie in said recess and the other to lie over the sunk mandrel surface when the mandrel and cutter are in a certain relative longitudinal position.
50. In witness that I claim the foregoing I have hereunto subscribed my name this 30th day of December, 1926.
55. JAMES J. SANTIAGO.
